UNITED STATES PATENT OFFICE

2,581,992

SMOKE PIPE TOP

Milton H. Wilder, Niles, Ohio, assignor to Wilder Products Company, Springfield, Ohio, a corporation of Ohio

Application July 30, 1949, Serial No. 107,661

3 Claims. (Cl. 98—83)

1

This invention relates to a smoke pipe top and more particularly to an adjustable smoke pipe top capable of being installed upon various diameters of smoke pipes.

The principal object of the invention is the provision of a smoke pipe top that may be installed on a number of different sizes of smoke pipes.

A further object of the invention is the provision of a smoke pipe top that can be shipped in a knocked-down form with the various parts nested so as to reduce shipping space.

A still further object of the invention is the provision of a smoke pipe top which can be readily assembled at the time of sale or installation from a few simple parts.

A still further object of the invention is the provision of a smoke pipe top which can be securely positioned on a large number of different sizes of smoke pipes.

The smoke pipe top shown and described herein comprises an improvement in the art in that it may be manufactured more easily, shipped more efficiently and assembled more rapidly than the smoke pipe tops heretofore known. Additionally, and importantly, the smoke pipe top may be adjusted to match the diameter of the particular smoke pipe on which it is to be installed as its structure is so arranged as to permit a wide degree of adjustment in this respect.

The smoke pipe tops heretofore known in the art have been factory assembled from a number of component parts including the conical top portion and the clamping or draw band, these portions usually being made up and assembled in a number of varying sizes which require a relatively large inventory on the part of the distributor as a different size of smoke pipe top was necessary for each different size of smoke pipe upon which the devices were to be positioned.

The present invention, on the contrary, makes it possible to make up one or two sizes of parts, assemble them into one or two sizes of smoke pipe tops and these in turn are capable of ready adjustment to the individual size of the smoke pipe on which they are to be positioned. Additionally, the common practice in the art has been to spot weld or securely fasten the various parts of the smoke pipe assembly to one another which required rather bulky shipping containers and the necessity of devoting a large storage area to the customary inventory.

The present invention is so devised that the top portion and the mounting portion are shipped

2

separately and assembled by sheet metal screws at the time of sale or installation. This enables the device to be shipped nested. A number of the units can, therefore, be placed in a single container which results in a savings in shipping costs and a marked savings in space needed for inventory of the devices.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawing, wherein:

20 Figure 1 is a side view of the smoke pipe top with parts broken away and parts in cross section.

Figure 2 is a top plan view of the smoke pipe top.

25 Figure 3 is a bottom plan view of the smoke pipe top.

Figure 4 is a bottom plan view showing the smoke pipe top adjusted to a different size.

By referring to the drawings and Figures 1, 2 and 3 in particular it will be seen that a smoke pipe top has been disclosed which comprises a top portion 10 which is conical in shape and of a desired diameter. An inverted transverse channel 11, having inturned flanges, is secured to the conical top portion 10 as by metal screws 12—12. Vertically positioned, horizontally movable brackets 13—13 are mounted with their uppermost ends 14—14 slidably engaged in the inverted channel 11 and in oppositely disposed relation with respect to one another. The brackets 13—13 are notched to provide clearance for the inturned flanges of the channel 11. A two-part draw band assembly 15 and 15A is positioned horizontally between the brackets 13—13 and secured thereto as by rivets 16.

The device thus far described will be seen to be adapted for positioning on the upper end of a smoke pipe with the draw band assembly clamped thereabout and the brackets 13—13 extending thereabove and supporting the top portion 10 in elevated relation to the upper end of the smoke pipe. In order that the draw band assembly may be clamped about a smoke pipe, each of the parts 15 and 15A thereof is substantially identical and positioned in oppositely dis-

posed relation to the other and each has an outwardly extending flattened U-shaped fold 17 and 17A thereon and each has a vertical crease 18 and 18A near one of the outermost ends thereof. Openings are formed in the flattened U-shaped folds 17 and 17A and in the end sections of the draw band adjacent the vertical creases 18 and 18A. The opposite ends of each of the two parts 15 and 15A of the draw band assembly have flattened U-shaped folds 19 and 19A, respectively, formed thereon at approximately right angles to the draw band and openings are formed in the flattened U-shaped folds 19 and 19A. These openings and those heretofore mentioned are formed in the draw band on the same horizontal plane so that nut and bolt assemblies 20 and 20A may be positioned therethrough as shown in Figure 3. It will be observed that the bolts 20 and 20A pass through the flattened U-shaped folds 17A and 18 and 17 and 18A, respectively.

It will be observed that the end sections of the two-part draw band assembly defined by the vertical creases 18 and 18A lie on the same circular pattern as the remainder of the draw band assembly 15 and 15A when the bolts 20 and 20A are positioned as shown in Figure 3 as the said end sections are flattened against the smoke pipe upon which the device is installed when the bolts 20 and 20A are positioned as just described to form a draw band of relatively small diameter.

In adjusting the draw band assembly for a larger size of pipe than permitted by the lengths of the bolts 20 and 20A, the bolts 20 and 20A are removed and re-positioned through the flattened U-shaped folds 15 and 15A, respectively, and the end sections of the draw bands adjacent the vertical creases 18 and 18A, respectively. Thus, the additional metal in each of the draw band parts 15 and 15A and lying between the flattened folds 17 and 17A and the vertical creases 18 and 18A is effectively added to the draw bands whereby a larger diameter of pipe may be secured therein. It will be obvious to those skilled in the art that it is necessary to bend the end sections of the draw band assemblies on the vertical creases 18 and 18A so that they extend outwardly at substantially right angles thereto. It will thus be seen that the two-part draw band assembly and the formation of the several flattened U-shaped folds therein as well as the vertical creases defining the end sections, as hereinbefore described, make possible the adjustability of the said draw band to many and various sizes of smoke pipes.

It will be obvious to those skilled in the art that in altering the diameter of the draw band assembly the horizontal spacing between the brackets 13-13 will of necessity change and by referring again to Figures 1 and 3 of the drawings it will be seen that when the device is adjusted for installation on a larger or smaller smoke pipe, the inturned ends 14 of the brackets 13, which are slidably engaged in the channel 11, are moved inwardly or outwardly as the case may be and secured in desired position as by self-tapping metal screws 21 as shown in Figures 3 and 4 of the drawings.

In Figures 2, 3 and 4 of the drawings additional brace members 21-21 are shown secured at their opposite ends to the opposite sides of the conical top 10 as by fasteners 22-22. The brace mem-

bers 21-21 may be bent downwardly and their lowermost ends engaged by the smoke pipe and the draw band assembly 15 and 15A as heretofore disclosed to additionally secure the assembly to the smoke pipe. Alternately, the brace members may be affixed to the smoke pipe if desired.

It will thus be seen that a smoke pipe top has been disclosed which meets the several objects of the invention and which provides a convenient and practical device which may be installed on any and all sizes and kinds of pipes as the same may be readily and easily adjusted to the particular size desired.

Having thus described my invention, what I claim is:

1. A smoke pipe top comprising in combination a conical top portion, an inverted channel secured to said conical top portion across the open end thereof, and a pair of inverted L-shaped brackets portions of which are slidably fastened in said channel and held thereby in oppositely disposed relation, and portions of which depend therefrom, a half-circular section of a draw band secured to the lower end of each of said depending portions of said brackets and in oppositely disposed relation to one another, and fasteners adjustably securing the ends of said half-circular sections of said draw band to one another.

2. A smoke pipe top comprising in combination a conical top portion, an inverted channel secured in said conical top portion crosswise thereof, said channel having inturned flanges, and a pair of notched inverted L-shaped brackets portions of which are slidably positioned in said channel in oppositely disposed relation, and portions of which depend therefrom, a half-circular section of a draw band secured to the lower end of each of said depending portions of said brackets and positioned in oppositely disposed relation to one another, and fasteners adjustably securing the ends of said half-circular sections of said draw band to one another.

3. A smoke pipe top comprising in combination a conical top portion, an inverted channel of a length sufficient to span the conical top portion at its widest point and removably secured thereto at its ends, a pair of notched brackets having the portions on one side of said notches slidably positioned in said channel and fastener means for removably securing the said brackets to the said channel, and a half-section of an adjustable draw band secured to the lower end of each of said brackets in oppositely disposed relation to one another and fasteners uniting the ends of the said draw bands.
